UNITED STATES PATENT OFFICE

117,372

DESIGN FOR A CREAMER

Charles Kaiser, Great Neck, N. Y., assignor to Morimura Bros., Inc., New York, N. Y., a corporation of Japan

Application June 21, 1939, Serial No. 85,612

Term of patent 7 years

To all whom it may concern:

Be it known that I, Charles Kaiser, a citizen of the United States and a resident of Great Neck, county of Nassau, and State of New York, have invented a new, original, and ornamental Design for a Creamer, of which the following is a specification, reference being had to the accompanying drawing, forming a part thereof.

Figure 1 is a side elevational view of a creamer showing my new design; and

I claim:

The ornamental design for a creamer, as shown.

CHARLES KAISER.
